COMBINED TWIN SOFA BED AND TABLE UNIT

David Bendell, 7240 SW. 125th St., Miami, Fla.

Filed May 27, 1964, Ser. No. 80,451

Term of patent 14 years

(Cl. D5—4)

FIG. 1

FIGURE 2 is a perspective view of same with the units converted to position for night time use; and

The rear of the unit is of conventional configuration.

This is a continuation-in-part of my prior application Serial No. D. 70,486, filed on June 8, 1962, which has been abandoned.

I claim:

The ornamental design for a combined twin sofa bed and table unit, substantially as shown and described.
